(57) **CLAIM**

(51) LOC (7) Cl. **13-03**

The ornamental design for an electrical connector, as shown
and described.

(52) U.S. Cl. **D13/133; D13/147**

DESCRIPTION

(58) Field of Search D13/133, 146,
D13/147; 439/108, 607, 608, 677-681

FIG. 1 is a front view of a electrical connector showing my
new design;

(56) **References Cited**

FIG. 2 is a top plan view thereof;

U.S. PATENT DOCUMENTS

FIG. 3 is a rear view thereof;

5,885,088 A * 3/1999 Brennan et al. 439/680
D412,700 S * 8/1999 Gardner et al. D13/147
D415,107 S * 10/1999 Avery et al. D13/147
D416,229 S * 11/1999 Narumo et al. D13/147
D416,539 S * 11/1999 Narumo et al. D13/147
D422,562 S * 4/2000 Huang D13/147

FIG. 4 is a right side view thereof; and,

FIG. 5 is a bottom plan view thereof.

The broken lines throughout the drawing figures are
included for the purpose of illustrating portions of the
connector that form no part of the claimed design.
